DEVICE FOR THE CONTROL OF MOTION OF
MOVABLE BLADES ON BLADE WHEELS

Josef Ehrhart, Heidenheim-on-the-Brenz, Germany, assignor to Voith-Schneider Propeller Company, New York, N. Y., a corporation of New York

Application March 23, 1935, Serial No. 12,670
In Germany March 26, 1934

11 Claims. (Cl. 170—148)

This invention relates to devices for the control of motion of movable blades on blade wheels in which the axes of the blades are parallel or substantially parallel to the axis of the rotor. One of the objects of the invention is a simplification of the means of control for the blades.

It is known that in accordance with hydraulic principles, the correct relative movement of such blades in respect to the blade supporting body or 10 blade wheel is then attained, when the normals to the blade profiles passing through the longitudinal axis of the blade, all intersect at all times in one certain point which is known as the steering center. Devices embodying this principle are 15 known. They operate either with an imaginary steering center or with a material steering center, which material steering center is provided with rods which are connected with the blades so as to operate or shift the blades, depending upon the 20 position of the steering center.

This form of embodiment results in a relatively high structure in the center part of such blade wheels, and in an unsatisfactory distribution of forces acting upon the steering center, and also in 25 that such an arrangement in different planes necessitates special construction of the rods and connecting links.

More particularly, the invention consists in arranging the connecting means between the 30 blades and the steering center substantially in a plane at right angles to the axis of rotation of the blades. By this arrangement, simplification in the manufacture, in the installation and in the operation is obtained, and a very compact structure results.

In an embodiment of the invention hereinafter shown, each blade is connected with the steering center by means of a rod, guided in a linear direction, by a guide block rotatably fixed upon the 40 blade wheel or rotor, said guide block determining the angular movement of the blades, since they are also connected with an eccentrically adjustable member or steering center plate, which when placed in the concentric position places the axis 45 of the horizontal profile of the blade tangential to the circle of rotation, corresponding to a propeller pitch of zero, the rods for all blades being arranged in the same radial plane.

The invention consists further in combining the 50 structure set forth with an electric propulsion means, part secured to the blade wheel rotor and part to the housing, this combination being made possible by the compact arrangement resulting from the arrangement of the before mentioned 55 rods.

The invention further provides specially advantageous means of overcoming certain operative deficiencies which will be pointed out hereinafter.

Embodiments of the invention will be herein-after described and shown in the drawings, and will be finally set forth in the appended claims.

In the drawings, in which same reference characters indicate same parts,—

Figure 1 is a plan view diagrammatically shown, 10 of a blade wheel with six blades and the connecting rods thereon for operating the blades during the rotation of the blade wheel, the blades being shown in their zero or tangential position, or in "stop" position;

Figures 2 is a section on line 2—2 of Fig. 1;

Figure 3 is a plan view diagrammatically shown, 15 similar to Fig. 1, but showing the blades in a position corresponding to the forward movement of the blade wheel when used as a propulsion means of a ship.

Figure 4 is a plan view of another embodiment 20 also diagrammatically shown;

Figure 5 is a diagrammatic representation of the movement of the operative parts of a blade relative to the rotor;

Figure 6 is a perspective view of a practical embodiment of the invention herein described;

Figure 7 is a vertical central cross section of one 25 of the above embodiments with an electric propulsion means combined therewith; and

Figure 8 is a plan view of Fig. 7.

Referring to the drawings and more particularly to Figures 1 and 2, the blade wheel or rotor 10 has its axis 11 of rotation centrally disposed in respect thereto. A plurality of blades 12 are 35 suitably supported by blade wheel 10 in movable position in respect thereto and the position of the blades shown in Figure 1 is in zero or tangential position corresponding to the "stop" position.

In the central part of the blade wheel, 40 a steering center plate 15 is arranged, which is rotatably connected with a ball 16 of the lever 17 pivoted at 18 in the socket 19, permanently held to the blade wheel hub 20, as shown in Figure 2. By moving the lever 17, the plate 15 is moved in any direction and the transposed position of the plate 15 is clearly shown in Fig. 3, wherein the plate 15 is eccentrically disposed to the axis 11 and the blades are shown angularly displaced in respect to the position shown in Figure 1. The lever 17 may be operated either by hand or by 50 any suitable device well known in the art and not shown in the drawings. In Figure 7, servomotors 47 are utilized. The steering center plate 15 is moved in both dimensions of the radial 55

plane and may take any position in respect thereto. The steering center plate 15 is connected by means of a pivotal connection 21 with a slide rod 22. Each of these slide rods 22 is connected with the blade wheel 10 by a guide block 23, the ends 5 of which engage suitable recesses 24 and 25 in the plates 26 and 27 of the blade wheel. The guide blocks 23 being rotatably held in their recesses, do permit the slide rods 22 to slide therethrough, in a straight line direction. Such plates 10 26 and 27 form a compartment of relatively small depth, in which the steering center plate 15 and the slide rods 22 and the other parts about to be described are arranged. Each of the slide rods 15 22 is pivotally connected with links 29 by the connection 30, and the free ends of the links 29 are connected with the blades 12 through the pivotal connection 31, and the blade lever 32, which blade lever 32 is suitably secured to the blade stem 33 of the blade 12. The movement of 20 the pivotal point 30 then determines the angular position of the blade 12 in respect to a circle 35 shown in dotted lines in Fig. 1, which circle 35 indicates the path of the blades as they rotate. 25 The pivotal connection 30 may be made in the form of a shear pin easily broken when the strain is too large. Any suitable safety breaking device may be utilized. The steering plate 15 rotates with the rotor 10, and to effect this rotation of the steering plate in the embodiment 30 shown in Figure 1, the steering plate 15 is integrally extended by means of the bar 36 which at its free end has a sliding connection 37 with a stud 38 secured to the blade wheel. The relative 35 movement between the fork-shaped end 37 and the stud 38 must be such that the largest possible movement of the steering plate 15 in any direction in its plane at right angles to the axis 11 will be permitted.

40 It will be noted that as the steering center plate 15 is moved into eccentric position as shown in Figure 3, the slide rods 22 slide in the guide blocks 23, and their free ends take different positions. The straight line movements of the slide rods 22, move the pivotal connection 30, and in consequence the links 29, and thereby the blade levers 32 and blades 12, whereby the blades 12 are angularly shifted.

45 In the embodiment shown in Figure 4, the same parts just described are utilized save that the bar 36 is omitted and the rotation of the steering center plate 15 is obtained by rigidly connecting with the plate 15 one of the slide rods which is marked in Figure 4 with the reference 50 39. This is in turn connected with the link 29, blade lever 32 and blade 12, and in consequence 55 as the blade wheel 10 rotates, the steering center plate 15 is rotated therewith.

60 In the described forms wherein the steering plate 15 is carried along by the blade wheel and rotated therewith, it will be noted that the movement of the former is not with a constant angular velocity, but with a variable one. It is possible to so arrange the coupling between the blade wheel and the steering center plate that both 65 parts rotate always with equal angular velocity, but whatever advantage may result therefrom would be overcome by an unnecessarily complicated construction of the parts. From a practical 70 standpoint the described coupling devices between the blade wheel and the steering center plate satisfy all practical conditions; it is self-evident that certain deviations of the parts of the control mechanism among each other result, depending upon their relative position to the 75

coupling rod 36 in Figure 1 and 39 in Figure 4. The lengths of the links 29 differ somewhat from each other, and the guide blocks 23 do not rest in a circle around the axis 11 of the rotor 10, as this would be the case with an exact coupling 5 10 effecting a constant angular velocity. Those deviations may be readily calculated and are of simple construction, but the difference between dimensions of one in respect to the other is so small that the practical form as herein described 15 has been given preference to the theoretically exact form. In the embodiments shown in Figures 1 and 4, the links 29 are of different lengths. The construction herein shown has all the essential advantages just set forth. 15

In the embodiments shown, the points of attachment of links 29 on the steering center plate 15, through the slide rods 22 are all in one and the same plane, so that the smallest possible construction height as also the most advantageous 20 stress distribution upon the steering center plate are obtained. The described device has also certain further advantages inasmuch as the throw of the blades is influenced in such a manner as has not been possible with heretofore known mechanical control devices used in similar blade wheels. 25

In the devices heretofore proposed, the point moving in a straight line was always fixed to the steering center or steering center plate and the free end of the connecting rod was pivotally connected with the rotating rotor. In consequence, the throw of the blade was always proportional to the throw of the connecting rod and the blade reached its largest throw exactly in the same point of time as the connecting rod. Kinematic 35 researches of the law of movement have shown that the two greatest amplitudes of the blade must follow each other in point of time all the quicker, the larger the propeller pitch is. In consequence thereof, the devices heretofore proposed caused 40 considerable difficulties so when blade wheels of great pitch were constructed, the entire mechanism including the connecting links had to be designed for largest amplitudes quickly following each other, whereby large accelerating forces and 45 unfavorable lever ratios were unavoidable.

In the arrangement in accordance with this invention, the point moving in a straight line is fixed to the blade wheel, whereby a periodic change of the speed ratio between the angular 50 movements of the rod 22 and the blade lever 32 takes place and in such a manner that the positions of the blade at their greatest throw follow quicker upon each other in point of time than those of the slide rod 22. The diagram shown in 55 Figure 5 shows in diagrammatic form these advantageous relations. The change in the speed ratio comes exactly into being in that the free length 40 of the slide rod 22 changes itself periodically so that the velocity of the point of 60 the pivotal connection 30 becomes in certain positions of the device particularly large which, in point of time, corresponds to the largest amplitudes quickly following each other. These relations are obtained when the device is so executed 65 or constructed that in a central or concentric position of the steering plate 15, the length of the slide rod 22 through its straight line guide is so divided, that the distance between the axis of the inner pivotal connection 21 and the point 23 70 is one-half to one-third of the total length of the rod 22; as the pivotal point 30 takes different positions along the diagram or curve 41, the pivotal point 31 moves in correspondence thereto, the points a, b, c, d, e, and f, a', b', c', d', e', f' and 75

a'', b'', c'', d'', e'' and f'', indicating like positions.

The compact construction of the device for the control of motion for movable blades on blade wheels described hereinabove, permits its combination with an electric motor, and enables the assembling structure to be built of specially strong elements to correspond with the demands made by large diameter structures. In blade wheel propellers it has been customary heretofore to use a horizontal shaft along the length of the ship, and connect this shaft with the vertical shaft of the blade wheel propeller. In other cases where a vertical shaft was dispensed with, the horizontal shaft was connected by gears to the rotor of the propeller laterally of the axis of the propeller. An embodiment of this form is shown in my co-pending application, Serial No. 716,018 filed March 17, 1934. In contrast to these forms of mechanical transmissions, the present form of compact blade actuating mechanism enables electrical mechanism to be installed, so as to drive the blade wheel in a very simple manner.

In Figure 7, an embodiment of this invention is illustrated, in which the blade wheel 10, blades 12, blade shifting mechanism for the blades generally indicated by 45, steering center operating mechanism generally indicated by 46, a servomotor 47 of known construction to operate the lever 46, are shown. The blade wheel housing 48 is provided with an extension 49, to which is secured an open electric rotor ring 50. Within this rotor 50, an electric stator 51 is secured to the stationary housing 52. Where electric current obtained from a suitable source of supply, is used to energize the coils of the electric rotor and stator, the ring 50 is rotated, and in consequence the blade wheel is rotated. It will be particularly noted that the propeller blade wheel has no shaft or its equivalent or any driving means, since the peripheral electric rotor and stator rings exert the propelling force to rotate the blade wheel. Either direct or alternating current can be used. This electrical installation is comparatively simple since the blade wheel rotor rotates with constant speed which simplifies the wiring and switchboard arrangement. It will also be noted that the stationary housing 52 extends downwardly into a bell-shaped portion 53 which supports suitable anti-friction bearings, the rotatable blade wheel which rotates by the aid of anti-friction bearings 54 around a central hub 55, which is supported by the frames 56. The only operative part of the mechanism for shifting the blades is the lever 46 for shifting the steering center plate, which lever in turn is operated in the embodiment shown by the servomotor 47. This servomotor 47 and part of the lever 46, are disposed within the electrical stator ring 51 and rotor ring 50. Thus the open interior of the electrical rings permits the steering mechanism to be located therein, whereby the entire device as described is self-contained and may be installed with simplicity of operation, having all the advantages of electrical operation.

My invention has been illustrated and described with some degree of particularity, but it is understood that changes may be made in the form of details and in the construction and arrangement of parts without departing from the spirit and scope of the invention or the scope of the appended claims.

I claim:

1. A device for the control of motion of movable blades on blade wheels, in which the blade

axes are substantially parallel to the axis of the blade wheel, blade controlling means for a blade wheel having blades, including a steering center plate rotating with said blade wheel and shiftable in any direction in a plane perpendicular to the axis of the blade wheel from a position concentric and corresponding with zero pitch of the blades to a position eccentric to said axis, and connecting means between said steering center plate and each blade including a rod for each blade pivoted to said steering center plate, guide means for said rod for guiding the same in straight line movement for controlling the angular motion of the blade. 5

2. A device for the control of motion of movable blades on blade wheels, in which the blade axes are substantially parallel to the axis of the blade wheel, blade controlling means for a blade wheel having blades, including a steering center plate rotating with said blade wheel and shiftable in any direction in a plane perpendicular to the axis of the blade wheel from a position concentric and corresponding with zero pitch of the blades to a position eccentric to said axis, connecting means between said steering center plate 20 and each blade including a slide rod for each blade pivoted to said steering center plate and guide means for said rod for guiding the same in straight line movement by said blade wheel, and a link pivoted at one end to the free end of said 30 slide rod and pivoted at its other end to one of said blades. 15

3. A device for the control of motion of movable blades on blade wheels, in which the blade axes are substantially parallel to the axis of the blade wheel, control means for a blade wheel having blades, including a steering center plate rotating with said blade wheel and shiftable in any direction in a plane perpendicular to the axis of the blade wheel from a position concentric 40 and corresponding with zero pitch of the blades to a position eccentric to said axis, connecting means between said steering center plate and each blade including a rod for each blade pivoted to said steering center plate and guide means for 45 guiding the rod in straight line movement, said guide means comprising a guide block rotatably mounted in said blade wheel for guiding the slide rod in straight line movement, and a link pivoted at one end to the free end of said slide 50 rod and pivoted at its other end to one of said blades. 35

4. A device for the control of motion of movable blades on blade wheels, in which the blade axes are substantially parallel to the axis of the blade wheel, blade controlling means for a blade wheel having blades, including a steering center plate rotating with said blade wheel and shiftable in any direction in a plane perpendicular to the axis of the blade wheel from a position concentric and corresponding with zero pitch of the blades to a position eccentric to said axis, connecting means between said steering center plate and each blade including a rod for each blade pivoted to said steering center plate and guide 60 means for guiding the rod in straight line movement, said guide means comprising a guide block for guiding said rod, said guide block being disposed in respect to the inner end of said rod a distance of one-half to one-third of the entire operative length of said rod. 65

5. A device for the control of motion of movable blades on blade wheels, in which the blade axes are substantially parallel to the axis of the blade wheel, blade controlling means for a blade 70

- wheel having blades, including a steering center plate rotating with said blade wheel and shiftable in any direction in a plane perpendicular to the axis of the blade wheel from a position concentric and corresponding with zero pitch of the blades to a position eccentric to said axis, connecting means between said steering center plate and each blade including a rod for each blade pivoted to said steering center plate and guide means for guiding said rod in straight line movement, and means for securing the steering center plate to said blade wheel, including a bar secured to said plate and to the blade wheel.
6. A device for the control of motion of movable blades on blade wheels, in which the blade axes are substantially parallel to the axis of the blade wheel, blade controlling means for a blade wheel having blades, including a steering center plate rotating with said blade wheel and shiftable in any direction in a plane perpendicular to the axis of the blade wheel from a position concentric and corresponding with zero pitch of the blades to a position eccentric to said axis, connecting means between said steering center plate and each blade including a rod for each blade pivoted to said steering center plate and guide means for guiding said rod in straight line movement, and means for securing the steering center plate to said blade wheel, including a bar secured to said plate and to the blade wheel, said bar having a sliding connection with a stud on the blade wheel.
7. A device for the control of motion of movable blades on blade wheels, in which the blade axes are substantially parallel to the axis of the blade wheel, blade controlling means for a blade wheel having blades, including a steering center plate rotating with said blade wheel and shiftable in any direction in a plane perpendicular to the axis of the blade wheel from a position concentric and corresponding with zero pitch of the blades to a position eccentric to said axis, connecting means between said steering center plate and each blade including a rod for each blade pivoted to said steering center plate and guide means for guiding said rod in straight line movement, and means for securing the steering center plate to said blade wheel, including a bar secured to said plate and to the blade wheel, said bar having a sliding connection with a stud on the blade wheel, the last named bar being so arranged that the steering center plate rotates with a constant angle of velocity.
8. A device for the control of motion of movable blades on blade wheels, in which the blade axes are substantially parallel with the blade wheel axis, comprising unitary structure consisting of a steering center plate movable in a plane perpendicular to the axis of the blade wheel, and rotatable with the blade wheel, sliding rods pivoted to said plate, guide means for guiding said sliding rods for movement in straight line direction by the said plate, and having means adapted to be connected with the blade wheel, and to be rotatable therewith, blade moving means adapted to be attached to the blades, links disposed between the free ends of said sliding rods and the blade moving means of said parts, the plate, the sliding rods, the blade moving means and the links being disposed substantially in one plane, and fastening means for rotating all of said parts with said blade wheel.
9. A device for the control of motion of movable blades on blade wheels, in which the blade axes are substantially parallel with the blade wheel axis, comprising unitary structure consisting of a steering center plate movable in a plane perpendicular to the axis of the blade wheel, and rotatable with the blade wheel, sliding rods pivoted to said plate, guide means for guiding said sliding rods for movement in straight line direction by the said plate, and having means adapted to be connected with the blade wheel, and to be rotatable therewith, blade moving means adapted to be attached to the blades, links disposed between the free ends of said sliding rods and the blade moving means of said parts, the plate, the sliding rods, the blade moving means and the links being disposed substantially in one plane, and fastening means for rotating all of said parts with said blade wheel.
10. A device for the control of motion of movable blades on blade wheels, in which the blade axes are substantially parallel with the blade wheel axis, comprising unitary structure consisting of a steering center plate movable in a plane perpendicular to the axis of the blade wheel, and rotatable with the blade wheel, sliding rods pivoted to said plate, guide means for guiding said sliding rods for movement in straight line direction by the said plate, and having means adapted to be connected with the blade wheel, and to be rotatable therewith, blade moving means adapted to be attached to the blades, links disposed between the free ends of said sliding rods and the blade moving means of said parts, the plate, the sliding rods, the blade moving means and the links being disposed substantially in one plane, and fastening means for rotating all of said parts with said blade wheel.
11. In combination, with a device for the control of motion of movable blades on blade wheels in which the blade axes are substantially parallel to the axis of the blade wheel, including a steering center plate movable with said blade wheel and shiftable in any direction in a plane perpendicular to the axis of the blade wheel from a position concentric to eccentric to said axis, connecting means between said steering center plate and said blades including a rod pivoted to said steering center plate, a guide for guiding said rod in straight line movement by said blade wheel, of a housing rotatable with said blade wheel, a flange on said housing, an electrical open ring rotor secured to said flange, a stationary housing, a flange on said stationary housing, an electrical open ring stator secured to said flange of the stationary housing, and means for operating the steering center plate arranged within the open space of said electrical ring rotor and stator.

JOSEF EHRHART.
